UNIVERSAL ARTICULATION DEVICE FOR
RAILWAY AND/OR TRAMWAY CARRIAGES
MOUNTED ON TRUCKSMario Urbini, Rome, Italy, assignor to the firm:
Officina Meccanica Della Stanga S. A., Padua,
ItalyApplication August 29, 1939, Serial No. 292,472.
In Italy September 7, 1938

4 Claims. (Cl. 105—4)

The present invention relates to railway and/or tramway carriages composed of articulated elements, and an object of the invention is to connect the various articulated elements to each other so as to enable passengers to freely pass from any element to the adjacent element.

According to the present invention, relative angular displacements in the horizontal plane of two adjacent elements is obtained by means of an articulation cylinder, while an elastic connection (such as, for instance, a rubber connection or small bellows) is provided merely to absorb angular movements due to rolling, rocking, uneven load, rupture of suspension springs, changes in grade, raised rails and imperforations of the track. The characteristics of the present invention will clearly appear from the following description, with reference to the attached drawings, wherein:

Figure 1 is a longitudinal sectional view of an articulation according to one embodiment of the invention, when the train elements are in alignment.

Fig. 2 is a horizontal section thereof on line X—X of Fig. 1.

Figs. 3 and 4 are cross-sectional and plan views of a swing bolster of a truck provided with the articulation.

Fig. 5 is a horizontal section similar to that of Fig. 2, when the vehicle is on a curve.

Fig. 6 is a diagrammatic vertical section on the line Y—Y of Fig. 2.

Fig. 7 is a vertical section on the line Z—Z of Fig. 2.

Fig. 8 is a vertical longitudinal section of a modification.

Fig. 9 is a horizontal section of said modification.

In the embodiment represented in Figs. 1 and 2, two adjacent elements A and B of the carriage are supported by the arms 1 and 2 respectively, on a spherical socket 3, whereby said elements are free to rotate in any plane around the socket centre C, independently from each other. Between said elements is inserted a cylindrical member L, consisting of two parts L₁ and L₂, herein-after called semicylinders, which lie in seats 17 formed in the arms 1 and 2, respectively, and are supported by means of pivots 4 and 5. The geometric axes of the pivots pass through C; and when the elements A and B are horizontal, as shown in Fig. 1, said axes are vertical and aligned.

The only movement performable by a semicylinder, with respect to the elements A, B bear-

ing the same, therefore, is the rotational movement around the pivot. Each semicylinder is fixed to the respective element not only by the pivot but also by top guides shown diagrammatically at 19, 20. Upon such rotation the outer surfaces of the vertical walls and of the ceiling of L₁ and L₂ slide on ribs 15 of the vertical walls and ceiling of the elements A and B, while the floors 16 remain in the seats 17 formed in the floors of said elements. The two semicylinders L₁ and L₂ are connected to each other and maintained in the respective position as appears in Figs. 2 and 6 by means of a connecting rod 6 with spherical pivots 7 and 8, said connecting rod being located approximately in the plane containing C, parallel to the track plane.

The symmetry plane NN (Figs. 2 and 5) of the combination of L₁ and L₂, owing to a link system 9, 9', 9'' (Figs. 2, 5, 7 and 9) jointedly connected to the two elements A and B, constantly coincides approximately with the bisecting plane of the angle formed by the longitudinal center lines of the elements A and B. The link system 9, 9', 9'' moves approximately in the same plane parallel to the track plane wherein the connecting rod 6 lies; the pivot 10 in the plane NN is fixed to either of the semicylinders whilst the pivots 11 and 12 (which are spherical) are fixed on A and B respectively.

As the two semicylinders do not fit to each other to provide continuity, as may be seen in Figs. 1 and 2, there are provided to complete the continuity of the carriage with the articulation:

(a) on the floor 16, two sectors 13 (Figs. 2, 6 and 7) fixed by hinges 14 to one of the semicylinders and slidably supported by the other semicylinder (in Fig. 2 one sector 13 only is represented);

(b) on the vertical walls and ceiling an extensible connection 18.

Consequently, the articulation provides rotational movements about C of the element A relatively to the element B also in the vertical plane perpendicular to the track. This independency of movement requires a special construction of the truck swing bolster 21. Since this single bolster cannot simultaneously follow the movements both of A and B, according to the present invention the swing bolster of the truck having the articulation is provided with four bogie shoes (Fig. 3); two of them P₁ and P₄ are rigidly connected to the bolster and face the corresponding sliding shoes 23, 24 of the element A (or element B) whereas the other two P₂ and P₃ are spring-

cushioned relatively to the bolster and face the sliding shoes 25, 26 of B (or A). By suitably dimensioning the springs interposed between the bolster and the shoes P₂ and P₃ it is possible to fix at will the values of the forces which must act on the shoes to allow movements of A with respect to B in the plane perpendicular to the track to take place. Slight play may be left between bogie shoes and sliding shoes.

According to the invention, the angular position of the cylinder L (composed of two semi-cylinders) is determined by the adjacent elements A and B by means of a bar-link system. It would be constructionally simpler to have the position of L determined by the underlying truck, by rigidly connecting the truck and cylinder for movement about C in the horizontal plane. It can be easily understood, however, why the link drive is preferable. If the cylinder and the underlying truck were rigidly connected for rotation about C in a vertical plane, when the traveling carriage passes from a straight path to a curve, or vice versa, the rotations of the element A relatively to L and of L relatively to B would take place in a succession of stages, since, if A precedes B in the traveling direction, when the forward truck enters the curve, the rotation A—L begins and it ceases when the truck in turn enters the curve; from this moment begins the rotation L—B which in turn comes to an end when the rear truck also enters the curve. If, however L is obliged to maintain its plane of symmetry NN constantly in the bisecting plane of the angle formed by the two longitudinal center lines of A and B, the rotations A—L and L—B begin simultaneously when the forward truck enters the curve, or issues therefrom, and cease simultaneously when the rear truck also enters the curve, or issues therefrom.

The rotations A—L and L—B take place, therefore, in periods of time twice as long and it can be readily understood that the maximum values of the angular speed and acceleration are reduced to one half, and, most important, the movements begin and end without sudden changes of acceleration, which does not happen when L is rigidly connected with the truck for rotation in a horizontal plane around C.

In order to oblige L to keep in the bisecting plane of the angle formed by the longitudinal planes of the end surfaces of A and B, the link system 9, 9', 9'' has been employed; it is obvious however, that any other of the known systems for obliging an element to maintain a center line coincident with a line bisecting a variable angle could be used. Instead of connecting L₁ to L₂ by means of a connecting rod 6, L₁ and L₂ may be simultaneously and independently driven by two equal link systems 9, 9', 9''.

In Fig. 1 the two pivots 4 and 5 are represented with their axes in vertical alignment with C, one pivot superposed over the other. Obviously, they might be replaced by circular guides lying in a same plane parallel to the track.

According to the embodiment represented in Figs. 1 and 2 and just described, the cylinder L is divided into two parts L₁ and L₂. The articulation can be constructed, however, without such division, as shown in Figs. 8 and 9, in which case L is pivotally supported by one of the two elements, for instance A. In such case:

(1) The part B₁, as it must constantly move with L, must be pivoted on the same pivots of L on A, which does not prevent it from being rigidly

connected to B₂ for movement in a horizontal plane;

(2) The sectors 14 and the extensible connection between L₁ and L₂ are eliminated and an extensible connection 18 is provided between B₁ and B₂;

(3) As the whole floor of B is connected to the part B₂ (Fig. 9) in the changes of grade, raised rails, uneven loads and the like, a slight step will be created between the floor of L and the floor of B.

What I claim is:

1. An articulation device for connecting adjacent vehicle elements, comprising in combination 15 a transverse frame member, a spherical joint system between said frame member and vehicle elements, said system including a joint member connected to each vehicle element, an open-ended cylindrical structure disposed between the ends of the vehicle elements and adapted to preserve passageway continuity between the same in their movements of articulation, a pivotal connection in a vertical axis between said cylindrical structure and said vehicle elements, the 20 axis of which connection is aligned with the center of the spherical joint, a jointed link system connecting the vehicle elements with capacity for articulation movements in a horizontal plane, means for guiding articulatory movements 25 of the cylindrical structure and vehicle elements in a vertical plane the cylindrical structure being formed in two halves capable of relative articulation in a vertical plane about said spherical joint, said halves being each pivoted to the respective adjacent vehicle element and connected to each other by a horizontal link with universal joints substantially in a horizontal plane passing through the spherical joint, and an extensible member being disposed between said halves for 30 preserving continuity of the side and top portions of the halves in their articulatory movements.

2. An articulation device for connecting the adjacent ends of adjacent vehicle elements comprising 35 a supporting frame member, a spherical joint system interconnecting the frame member and vehicle elements, a cylindrical structure positioned between and extending into the adjacent ends of the vehicle elements, and provided 40 with diametrical passageway openings to afford communication between the adjacent connected vehicle elements, said cylindrical structure being formed in two halves, one half being pivotally mounted in the end of one vehicle element and the other half being pivotally mounted in the end of the adjacent vehicle element, a link universally connected to the halves at one side of their pivotal axes at the lower portions thereof to limit relative horizontal pivoting movement, 45 and extensible surfacing material extending between the two halves to preserve side and top surface continuity between the halves upon relative movement in a vertical plane due to relative movement of the vehicle elements in a vertical 50 plane about the joint system.

3. An articulation device for connecting the adjacent ends of adjacent vehicle elements comprising 55 a supporting frame member, a spherical joint forming surface on said frame member, an arm extending from the end of one vehicle element and having a spherical joint forming surface provided thereon, an arm extending from the end of the adjacent vehicle element, and having 60 a portion extending between and having sur-

faces cooperating with the spherical joint forming surfaces of the frame member and the first recited arm to form a spherical joint interconnecting the vehicle elements and frame, a semi-cylindrical vestibule forming member pivotally mounted in the end of each vehicle element for pivotal movement relative to the vehicle element about a vertical axis passing through the center of said spherical joint, said semi-cylindrical members having passageway openings in the sides thereof to afford communication with the vehicle elements, and extensible surfacing material joining adjacent semi-cylindrical members to provide surface continuity between the same while permitting said semi-cylindrical members to move relatively to each other in a vertical plane about the spherical joint.

4. An articulation device for connecting the adjacent ends of adjacent vehicle elements comprising a supporting frame member, a spherical joint forming surface on said frame member, an arm extending from the end of one vehicle element and having a spherical joint forming surface provided thereon, an arm extending from

the end of the adjacent vehicle element, and having a portion extending between and having surfaces cooperating with the spherical joint forming surfaces of the frame member and first recited arm to form a spherical joint interconnecting the vehicle elements and frame, a semi-cylindrical vestibule forming member pivotally mounted in the end of each vehicle element for pivotal movement relative to the vehicle element about a vertical axis passing through the center of said spherical joint, said semi-cylindrical members having passageway openings in the sides thereof to afford communication with the vehicle elements, extensible surfacing material joining adjacent semi-cylindrical members to provide surface continuity between the same while permitting said semi-cylindrical members to move relatively to each other in a vertical plane about the spherical joint, and means universally connecting adjacent semi-cylindrical members at their lower portions at one side thereof to limit relative horizontal movement between connected semi-cylindrical members.

MARIO UREBINATI.
